UNITED STATES PATENT OFFICE.

JOSEPH ALONZO GIBSON, OF SACRAMENTO, CALIFORNIA.

SCREW-HOLDING ATTACHMENT FOR SCREW-DRIVERS.

1,159,016.

Specification of Letters Patent.

Patented Nov. 2, 1915.

Application filed March 8, 1915. Serial No. 13,202.

To all whom it may concern:

Be it known that I, JOSEPH ALONZO GIBSON, a citizen of the United States, residing at Sacramento, in the county of Sacramento and State of California, have invented new and useful Improvements in Screw-Holding Attachments for Screw-Drivers, of which the following is a specification.

This invention relates to screw holding attachments for screw drivers.

The invention has for its object to produce a simple and effective device capable of being easily and quickly applied to an ordinary screw driver for the purpose of holding the screw in position with respect to the driver blade, enabling the screw to be applied and started with one hand.

A further object of the invention is to so arrange the screw holding member that when not required for use, after starting the screw, it may be readily moved to an out-of-the-way position.

A further object of the invention is to simplify and improve the construction and arrangement of the component parts of the device.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing.—Figure 1 is a side view showing the holding device applied to an ordinary screw driver in position for operation. Fig. 2 is a perspective view of the holding device detached. Fig. 3 is a transverse sectional view taken on the line 3—3 in Fig. 1. Fig. 4 is a transverse sectional view taken on the line 4—4 in Fig. 1.

Corresponding parts in the several figures are denoted by like characters of reference.

The improved device comprises a rectangular frame 15 provided at the ends thereof, adjacent to one side, with openings 16 for the passage of the shank 17 of an ordinary screw driver on which the frame may be

securely retained in adjusted position by means of a set screw 18 bearing against the shank 17 and holding it forcibly against the walls of the openings 16, the screw 18 being threaded through one side member of the frame. The ends of the frame are provided adjacent to the other side member with openings 19 for the passage of a rod 20 having a thumb piece or handle 21 at one end adjacent to the handle 22 of the screw driver. The rod 20 is provided with a pin 23 extending transversely therethrough and engaging at one end a slot 24 in the proximate side member of the frame, said pin serving the three-fold purpose, first, of limiting the sliding movement of the rod, second, of preventing the rod from turning about its axis, and third, to form an abutment for one end of a helical spring 25 which is coiled about the rod, and the other end abuts on one end of the frame, thereby forcing the rod 20 rearwardly in the direction of the handle of the screw driver. Pivots connected with the forward end of the rod 20 which extends beyond the frame 15 is an arm 26 which constitutes a screw holding member, said arm being provided at its free end with a bifurcated claw 27 to engage the shank of a screw, the latter being seen at 28. The arm 26 is pivotally connected with the rod 20 by means of a screw 29 which permits the parts to be readily assembled or disassembled.

In operation, the frame 15 is mounted on the shank of the screw driver in such a position that the bit 30 of the latter will engage between the prongs of the bifurcated claw 27. By pushing on the thumb piece 21 the rod 20 with the arm 26 will be moved forwardly, thus permitting a screw to be adjusted by placing its shank between the prongs of the claw 27 with its head impinging on said prongs, after which by releasing pressure on the thumb piece 21, the rod will be retracted by the action of the spring 25, permitting the bit of the blade to engage the notch of the screw which will thus be securely held while being started. After starting the screw, the holding device may be disengaged therefrom, and the arm 26 having the retaining claw 27 may then be turned to the out-of-the-way position shown in dotted lines in Fig. 1, thus enabling the screw driver to be manipulated in the customary manner for tightening the screw and driving it home.

It will be seen from the foregoing that I

have produced a very simple and effective screw holding device or attachment which may be quickly and readily applied to an ordinary screw driver. It is obvious that the appliance may be made in different sizes and also that the slots or openings for the passage of the shank of the screw driver may be modified according to the shape and character of such shank.

10 Having thus described the invention, what is claimed as new, is:—

In a screw holding attachment of the class described, a frame having openings for the passage of a shank of a screw driver, and 15 means for securing it adjustably on said shank, one side member of said frame being provided with a longitudinal slot, a slideable rod extending longitudinally through the

frame and having a thumb piece at one end, an actuating spring for said rod, a pin 20 extending through the rod and engaging the longitudinal slot in the frame to limit the movement of the rod, to prevent it from turning about its axis and to form an abutment for one end of the actuating spring, 25 and an arm connected pivotally with the forward end of the rod that extends through the frame and having a screw holding bifurcated claw.

In testimony whereof I affix my signature 30 in presence of two witnesses.

JOSEPH ALONZO GIBSON.
